ARTICLE SUPPORT STAND**Donald O. Osier, Fresno, Calif.****Application December 8, 1955, Serial No. 551,779****3 Claims. (Cl. 280—41)**

The present invention relates to stands and more particularly to a stand for supporting articles which is portable, collapsible and mobile.

In the masonry trade it is standard practice to provide support for a mortar board and devices for such a purpose are appropriately known in the art as mortar board stands. In use, a mortar board is normally loaded with mortar and then rested on a stand at a convenient height above the floor or ground to facilitate access to the mortar for application to building walls, ceilings and the like by a mason or other worker.

In the past mortar board stands have assumed numerous forms. An early type consisted of an upstanding, generally rectangular wooden frame on which a mortar board was rested. These frames were bulky, not collapsible, difficult to store and transport, and not mobile. Later developments include elongated sets of legs pivotally connected in X shape, and rectangular frames likewise connected in an X configuration pivotally joined for opening and folding. These frames are ordinarily held against collapse in their open or erected positions by chains or like members. Although the latter stands are portable and collapsible, they are not mobile and in some instances of inadequate durability to perform their intended functions.

Mobility has been found to be a highly desirable characteristic in a mortar board stand. While plastering a wall or ceiling of a large room, for example, it has often been necessary, with conventional mortar board stands which are not mobile, to walk back and forth repeatedly from the stands to the areas of application of the mortar in order to obtain fresh amounts of mortar as required. This obviously results in much delay, inconvenience and consequent expense. Of course, stands of the prior art could be moved but generally only by first removing the mortar board supported thereon and then picking the stand up and placing it in a new location whereupon the mortar board was again positioned thereon. Such a procedure is time consuming, inefficient, clumsy and subject to the spilling of mortar.

Although the invention is described for use in supporting a mortar board and is excellently suited for such a purpose, it will be evident as the description proceeds that the disclosed stand is adapted to support a variety of articles and is not necessarily limited to the use which motivated its development.

Accordingly, an object of the present invention is to provide a supporting stand which is mobile, portable, and collapsible.

Another object is to provide an article supporting stand which may be collapsed into compact form for easy handling, storing and transporting.

Another object is to provide a stand for supporting large and bulky materials of considerable weight which is easily moved notwithstanding the positioning of such articles or materials thereon.

Another object is to provide a lightweight stand of the character described which is durable and especially capa-

2

ble of withstanding strain and dependably supporting heavy loads thereon.

Another object is to save time, labor and expense in the masonry art by providing an improved mortar board stand.

Another object is to provide a mortar board stand which enables the easy loading of a mortar board positioned thereon and movement thereof, as desired, to the exact location of application of mortar and the like in building construction.

Another object is to provide a stand of the character described which is simple and economical to make and use, light in weight, adapted to many uses, and which is highly effective in performing its intended functions.

These and other objects will become more fully apparent upon reference to the following description.

In the drawings:

Fig. 1 is a perspective view of an article supporting stand as provided by the present invention in erected position and showing the outline of a mortar board positioned thereon in dashed lines.

Fig. 2 is a top plan view of the stand shown in Fig. 1.

Fig. 3 is a somewhat enlarged fragmentary rear view 25 of a portion of the support stand taken from a position represented by line 3—3 at the left of Fig. 2 and looking forwardly at the stand.

Fig. 4 is a somewhat enlarged fragmentary transverse section taken on line 4—4 of Fig. 2.

Fig. 5 is a somewhat enlarged fragmentary view of a portion of the stand taken from a position represented by line 5—5 at the right of Fig. 2 looking rearwardly at the stand.

Fig. 6 is a rear elevation of the stand of Figs. 1 and 2 shown in collapsed condition.

Fig. 7 is a side elevation of the stand in collapsed condition as viewed from the left of Fig. 6.

Referring with greater particularity to the drawings:

A stand constructed in accordance with the present invention is shown in the drawings as including a rigid, substantially rectangular open main frame 11 having an upper end 12 and a lower end 13. The main frame includes a pair of spaced parallel longitudinal bars 14 extended between the upper and lower ends of the frame, an upper transverse bar 15 interconnecting the upper ends of the longitudinal bars, and a lower transverse bar 16 interconnecting the lower ends of the longitudinal bars. The bars are preferably of hollow tubular metallic construction of considerable rigidity but relatively light in weight. The lower bar 16 may be omitted, if preferred.

Stub axles 20 extend axially endwardly of the lower transverse bar 16 and support wheels 21 are journaled thereon. The support wheels are preferably but not necessarily rubber tired and are releasably held on the axles by cotter pins 22.

A rigid substantially rectangular open auxiliary frame 26, preferably of the same material as the main frame 11, also has an upper end 27 and a lower end 28. The auxiliary frame provides a pair of spaced longitudinal bars 29 extended between the upper and the lower ends of the frame terminating in angularly extended foot portions 30 at the lower ends thereof. An upper transverse bar 31 interconnects the upper ends of the longitudinal bars 29, and a lower transverse bar 32 interconnects the longitudinal bars adjacent to the lower ends thereof but spaced upwardly somewhat from the foot portions. The lower transverse bar thus imparts needed rigidity to the auxiliary frame at its lower end. In addition, a pair of resilient latches 33 extend outwardly from the bars 29 adjacent to the lower transverse bar 32 for purposes which will soon be described.

The main frame 11 and the auxiliary frame 26 are in-

terconnected by a pivot rod 35 extended through the longitudinal bars 14 and 29 intermediate their opposite ends to enable pivotal movement of the frames between an open, extended or erect position, such as shown in Fig. 1, and a collapsed or folded position, such as shown in Fig. 7. Obviously, any other arrangement than the rod 35 may be provided to pivotally interconnect the frames. The frames are thus connected in the general shape of an upright X and when erect the foot portions 30 of the auxiliary frame 26 are adapted to be in substantially perpendicular relation to any support surface on which the stand 10 rests. Further, in the erect position of the frames, the auxiliary frame is forwardly inclined at about a 45° angle, and the main frame is rearwardly inclined at about a 45° angle. These angular dispositions are by no means critical but serve to illustrate more specifically the described embodiment of the stand.

The upper transverse bar 31 of the auxiliary frame 26 provides a bore 40 centrally transversely extended therethrough and adapted to be disposed in an erect position when the stand 10 is erect, as in Fig. 1. A U-shaped plate 41 constituting a brace receptacle is mounted, as shown in Fig. 5, on the upper transverse bar 31 below the bore 40. A bearing collar 42 is rotatably mounted on the upper transverse bar 15 of the main frame 11 and is maintained against axial sliding movement in a central position on the bar 15, by bosses 43 extended from the bar 15 at both ends of the collar. An elongated rigid brace 44 of rectangular cross section provides an inner or rearward end 45 secured to the bearing collar 42 and an extended or forward end 46 providing an aperture 47 therein. It is to be noted that the brace is slightly longer than the distance between the upper transverse bars 15 and 31 when frames 11 and 26 are in the desired erect position so that the extended end 46 may be slidably fitted in the brace receptacle 41.

A lock pin 50 is adapted to be releasably slidably received through the bore 40 and aperture 47 in the brace 44, when the latter is in the brace receptacle 41, and is conveniently connected to the upper transverse bar 31 by means of a flexible chain 51, as best seen in Figs. 4 and 5, to prevent loss thereof.

A pair of elongated handle bars 55 provide inner or forward ends 56 on which are mounted sleeve bearings 57 journaled on the upper transverse bar 31 of the auxiliary frame 26. The handle bars also have extended outer or rearward ends 58 disposed for gripping convenience. A transverse bar 59 interconnects the handle bars intermediate their ends and in a position spaced from their inner ends a distance substantially equal to the distance between the upper transverse bars 15 and 31 when the frames 11 and 26 are erect and the pin 50 is extended through bore 40 and aperture 47.

The handle bars 55 are thus adapted for pivotal movement between a position folded or rested against the auxiliary frame 26 and a substantially horizontal position extended through the main frame 11 and beneath the upper transverse bar 15. In this latter position the transverse bar 59 interconnecting the handle bars lies immediately beneath the upper transverse bar 15.

A latch sleeve or receiver 65 is mounted on the bearing collar 42 generally diametrically opposite to the brace 44. A pair of U-shaped latch straps 66 are mounted in spaced axially aligned positions on the transverse bar 59 which connects the handle bars 55 and in positions adjacent to the latch sleeve when the transverse bar 59 is sub-adjacent to the transverse bar 15. A latch bolt 67 is slidably fitted in the straps 66 and includes a locking finger 68 adapted to be releasably slidably extended into the latch sleeve and a manipulating portion 69 adapted as a handle to move the bolt between latched and unlatched positions.

Operation

The operation of the described embodiment of the present invention is believed to be readily apparent and is briefly summarized at this point. In order to set up the stand, the main and auxiliary frames 11 and 26, respectively, are pivoted apart into an open upright X form, as shown in Fig. 1. The brace 44 is pivoted upwardly and the extended end 46 thereof slidably fitted into the brace receptacle 41. With the aperture 47 in the brace in registration with the bore 40, the lock pin 50 is dropped through the bore and the aperture. This locks the frame in an erect position.

The handle bars 55 are then pivoted upwardly into substantially horizontal positions and the latch bolt 67 pulled back, if necessary, and then pushed forwardly to insert the locking finger into the latch sleeve 65. This locks the handle bars into their upper positions with the outer ends 58 extended rearwardly beyond the upper transverse bar 15 of the main frame 11.

In use, a mortar board, or the like, indicated in outline by the dashed lines at 75, is positioned on the stand 10, being rested on the upper ends 12 and 27 of the frames 11 and 26. It will be noted that the periphery of the board may overhang the transverse bars and the handle bars 55 a considerable distance, if desired. The handle bars are made sufficiently long to enable convenient and adequate grasping area so that large and bulky items may be supported without interfering with the maneuverability of the stand.

It is next desirable to load the board 75 with mortar, or the like. This is easily done by grasping the handle bars 55 and moving the stand 10 together with the mortar board to the source of mortar. After the board is loaded it may be moved on the stand to any desired location where the mortar is to be applied. The lengthy handle bars not only clear the mortar board but offer a decided mechanical advantage in the leverage afforded. At the desired location, the foot portions 30 maintain the mortar board in substantially horizontal position and hold the stand stationary. It will be evident that the incorporation in the stand of the brace 44 and the handle bars 55 imparts extra durability to the stand for dependably supporting the mortar board and load thereon.

The stand 10 is collapsed after first removing the board 75 by releasing the latch bolt 67 from the sleeve 65 to permit the handle bars 55 to be folded or to drop downwardly against the auxiliary frame 26. It is to be noted at this point that it may be desirable under certain circumstances to drop the handle bars even when the mortar board is positioned on the stand. Such would be desirable when working in a limited space or when desiring to move with greater ease around the mortar board. Of course, the brace 44 maintains the frames 11 and 26 in dependable erect positions notwithstanding the release of the handle bars into folded condition.

Assuming, however, that the stand 10 is to be completely collapsed, the lock pin is next removed from the bore 40 and aperture 47 to permit the brace 44 to be removed from the brace receptacle 41. With the brace thus removed, it pivots downwardly on the bearing collar 42 and enables folding of the frames 11 and 26 into closed position, as shown in Figs. 6 and 7.

In its collapsed condition, the stand is easily carried, stacked, transported and stored. Additionally, the stand may be drawn, pulled or pushed on the support wheels 21 by grasping the upper transverse bars 15 and 31.

Further, the stand 10 is adapted to be supported on a scaffold, or the like, not shown, if desired, rather than on the floor or ground. For this purpose, the handles 55 are dropped against the auxiliary frame 26 and are held in place by latches 33 which spread outwardly and resiliently latch over the handles. The stand is then rested in inverted position on the scaffold with the wheels 21

upwardly disposed. A mortar board, as 75, may then be supported on the wheels and the foot portions 30 in a convenient manner.

From the foregoing it will be apparent that a support stand has been provided which is mobile, sturdy and durable but which is easily collapsed for storage and transport. The stand is easily manipulated, and excellently suited for handling bulky, heavy objects. It has been found to result in savings of time, labor and effort in applying mortar and the like in its use as a mortar board stand. As explained, it will be evident that the invention has many other uses although excellently suited for the described purposes.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described my invention, what I claim as new and desire to secure by Letters Patent is:

1. A portable, mobile, collapsible stand adapted to support a mortar board comprising main and auxiliary substantially rectangular support frames having spaced longitudinal bars providing upper and lower ends, and upper transverse bars extended between the upper ends of their respective longitudinal bars; a pivot rod substantially parallel to the transverse bars interconnecting the longitudinal bars of the frames at corresponding positions intermediate their upper and lower ends for movement between an expanded position with the main frame rearwardly inclined and the auxiliary frame forwardly inclined and a collapsed position with the frames folded against each other; support wheels rotatably mounted on the lower end of the main frame; a sleeve journaled on the upper transverse bar of the main frame; an elongated brace having an inner end connected to the sleeve, the brace also having an outer end; means releasably connecting the outer end of the brace to the upper transverse bar of the auxiliary frame when the frames are in expanded position; a pair of elongated handle bars having inner and outer ends; a transverse bar extended between the longitudinal bars intermediate the inner and outer ends, the inner ends of the handle bars being pivotally connected to the upper transverse bar of the auxiliary frame for movement of the handle bars into a substantially horizontal position with the transverse bar thereof adjacent to the upper transverse bar of the main frame; and latch means releasably interconnecting the upper transverse bar of the main frame and the transverse bar interconnecting the handle bars.

2. A portable, mobile, collapsible stand comprising a pair of substantially rectangular support frames having upper and lower ends, longitudinal bars extended between their respective upper and lower ends, and upper transverse bars extended between their respective longitudinal bars; pivot means interconnecting the longitudinal bars of the frames at corresponding positions intermediate their upper and lower ends pivotally interconnecting the frames in substantially X-shaped arrangement for movement between an expanded position with one of the frames rearwardly inclined and the other frame forwardly inclined and a collapsed position with the frames folded against each other; support wheels rotatably mounted on the lower end of the support frame adapted to be rearwardly inclined; a substantially U-shaped strap downwardly extended from the upper transverse bar of the support frame which is adapted to be forwardly in-

clined, such transverse bar having a transverse bore extended therethrough oppositely of the strap; a sleeve journaled on the upper transverse bar of the support frame adapted to be rearwardly inclined; an elongated brace having an end connected to the sleeve and an opposite end provided with an aperture adapted to be releasably slidably fitted in the strap with the aperture in registration with the bore in the transverse bar adjacent thereto; a pin slidably fitted through the bore of the upper transverse bar and the aperture in the brace; a pair of elongated handle bars having inner and outer ends; a transverse bar extended between the handle bars intermediate the inner and outer ends, the inner ends of the handle bars being pivotally connected to the upper transverse bar of the support frame adapted to be forwardly inclined for movement of the handle bars into a substantially horizontal position with the transverse bar thereof adjacent to the upper transverse bar of the support frame rearwardly inclined; a latch collar mounted on the sleeve; and a locking bolt slidably mounted on the transverse bar interconnecting the handle bars for movement into locking engagement with the latch collar on the sleeve.

3. A support stand comprising a pair of substantially rectangular frames each having elongated side members providing upper and lower ends and transverse end members interconnecting the upper ends, the lower ends of the side members being adapted to rest on a support surface, means pivotally interconnecting the frames at corresponding positions intermediate their ends; a sleeve rotatably mounted on one of the transverse end members intermediate the side members of its respective frame; a brace having an end rigidly mounted on the sleeve and providing an opposite end transversely extended therefrom, lock means mounted on the transverse end member opposite to the sleeve releasably engageable with the extended end of the brace to hold the upper ends of the frames in predetermined spaced relation, the brace being pivotal about the end member on which the sleeve is mounted between a bracing position extended between the upper ends of the frames and a retracted position between the side members of the frame on which the sleeve is mounted; a pair of handle bars pivotally mounted on the transverse end member on which the lock means is mounted for pivotal movement between a retracted position adjacent to the side members of the frame of said transverse end member and an operable position extended from the transverse end member on which they are mounted transversely of the opposite transverse end member; a latch borne by the handle bars in a position adjacent to the sleeve when the handle bars are in operable position having a bolt reciprocably movable in a rectilinear path substantially parallel to the sleeve; and a latch bolt receiver mounted on the sleeve positioned to receive the bolt of the latch by pivotal movement of the brace to bracing position.
